US00D844324S

(12) United States Design Patent (10) Patent No.: US D844,324 S
Hoppe et al. (45) Date of Patent: * Apr. 2, 2019

(54) BAG

(71) Applicant: Milwaukee Electric Tool Corporation,
Brookfield, WI (US)

(72) Inventors: Christopher S. Hoppe, Milwaukee, WI
(US); Steven W. Hyma, Milwaukee,
WI (US); Grant T. Squiers, Cudahy,
WI (US); Michael Stearns, Milwaukee,
WI (US)

(73) Assignee: Milwaukee Electric Tool Corporation,
Milwaukee, WI (US)

() Term: 15 Years

(21) Appl. No.: 29/592,233

(22) Filed: Jan. 27, 2017
